US00D613994S

(12) United States Design Patent
Murphy et al.

(10) Patent No.: US D613,994 S
(45) Date of Patent:  Apr. 20, 2010

(54) USER INTERFACE

(75) Inventors: Kyle Allen Murphy, Burke, VA (US);
Graham Sadtler, New Bern, NC (US)

(73) Assignee: BSH Home Appliances Corporation,
Huntington Beach, CA (US)

() Term: 14 Years

(21) Appl. No.: 29/270,171

(22) Filed: Dec. 15, 2006

(51) LOC (9) Cl. 07-02

(52) U.S. Cl. D7/406

(58) Field of Classification Search D7/304,

D7/346, 350.1, 350.3-4, 348-349, 351, 355,
D7/397, 402, 405, 406; D13/177; D15/89;
D32/28; 34/88, 524; 126/19 M, 275 E, 183,
126/52, 19 R, 42, 39 B, 190, 198, 1 R, 37 R,
126/39 R, 21 R, 273 A; 219/756-758, 679-680,
219/725, 727, 734, 435
